DESIGN FOR A GAS GRIDDLE

Russell T. Boardman, Los Angeles, Calif., assignor
to Wolf Range & Mfg. Co., Los Angeles, Calif., a
partnership comprising Hyman Wolf and A. I.
Wolf

Application April 21, 1941, Serial No. 100,536

Term of patent 7 years

To all whom it may concern:

Be it known that I, Russell T. Boardman, a citizen of the United States of America, residing at Los Angeles, in the county of Los Angeles and State of California, have invented a new, original, and ornamental Design for a Gas Griddle, of which the following is a specification, reference being had to the accompanying drawing, forming a part thereof.

The figure is a perspective view showing the

top, front, and one end of a gas griddle showing my new design. The other end is identical with the end seen in the figure, and the back is identical in shape with the front, but slightly higher, as shown.

I claim:

The ornamental design for a gas griddle, as shown and described.

RUSSELL T. BOARDMAN.
